UNITED STATES PATENT OFFICE.

FRANK M. MEAD, OF BOYLSTON, MASSACHUSETTS, ASSIGNOR OF ONE-HALF TO HENRY A. FOWLER, OF WORCESTER, MASSACHUSETTS.

COIN-HOLDER.

1,274,739.

Specification of Letters Patent. Patented Aug. 6, 1918.

Application filed April 10, 1916. Serial No. 90,019.

To all whom it may concern:

Be it known that I, FRANK M. MEAD, a citizen of the United States, residing at Boylston, in the county of Worcester and 5 Commonwealth of Massachusetts, have invented a new and useful Improvement in Coin-Holders, of which the following is a specification, accompanied by drawings forming a part of the same.

10 My invention relates to a coin holder for containing coins of a single denomination, which are frequently used, such for example, as nickels, used for car fares, and it has for its object to provide a convenient holder for 15 such coins which may be carried in the pocket, with one end protruding therefrom to afford convenient access, and which can be operated when held by one hand, to deliver a single coin. These objects, among 20 others, I accomplish by the construction and arrangement of parts as hereinafter described and illustrated in the accompanying drawings, in which—

Figure 1 represents one of my improved 25 coin holders shown as held in the pocket.

Fig. 2 is an elevation showing one edge of the holder.

Fig. 3 is a central longitudinal sectional view.

30 Fig. 4 is a central longitudinal sectional view on a plane at right angles to the section shown in Fig. 3, showing the holder in an inverted position, with one of the coins protruding therefrom.

35 Fig. 5 is a similar sectional view to Fig. 4 but showing the coin holder reversed, bringing the protruding coin in position to be withdrawn.

Fig. 6 represents the same view in section 40 as Fig. 3, but having the delivering nozzle turned to register with the second chamber of the coin holder.

Similar reference characters refer to similar parts in the different figures.

45 My improved coin holder consists of a flattened tube 1 having a central partition 2 dividing the tube into two separate chambers 3 and 4. Each of said chambers is adapted to receive a definite number of coins 50 of the desired denomination. The coin holder is represented in the accompanying drawings as adapted for holding nickels and each of the chambers 3 and 4 is of the proper size to hold five nickels in each chamber, when the latter are filled. The

chambers 3 and 4 are closed at their lower end and open at their upper end. Over the open end of the chambers is slipped a nozzle 5 fitting the tube 1 sufficiently tight to enable it to be held by friction against accidental displacement. The nozzle 5 is provided with a single channel 6 of the proper size to allow the passage of a coin. When placed in position the channel 6 registers with one of the chambers in the tube 1. Upon the end walls of the nozzle 5 are placed the bent springs 7 and 8 conveniently held upon the tube by rivets 9, 9. From their point of attachment by the rivets 9, 9, the springs are bent inwardly as at 10, 10, to project into the path of the coin. From the bends 10, 10, the springs extend outwardly, as shown at 11, 11, and from the bends 11, 11, the springs are again bent inwardly, as at 12, 12, with the ends 13 of the springs bearing against the inner wall of the nozzle. The nozzle 5 is removed from the end of the tube and the chambers 3 and 4 are filled with coins. The nozzle is then replaced with the channel 6 in alinement 70 with one of the chambers 3 and 4, as represented in Fig. 3, where the channel 6 is shown in alinement with the chamber 3. The nozzle 5 is provided with a shoulder 14, which, in the position shown in Fig. 3, 75 serves to close the chamber 4.

When it is desired to withdraw one of the coins, the coin holder is removed from the pocket and inverted with a slight flinging motion which serves to carry one of the 80 coins by its momentum past the bends 10, 10 of the springs. The force required to compress the springs by passage of a coin checks the momentum of a coin, allowing it to be grasped by the concave sections 11, 11 which 85 embrace the sides of the coin and hold the latter with a portion of its surface protruding from the end of the nozzle 5. The holder is then reversed to bring the protruding coin uppermost, allowing it to be 90 removed.

When the nickels have been removed from the chamber 3, the nozzle 5 is withdrawn from the end of the tube 1, turned half way around, and replaced, bringing 105 the channel 6 in alinement with the chamber 4, as shown in Fig. 6. My improved coin holder is especially adapted for the payment of nickel car fares, allowing the holder to be removed from the pocket with one 110

hand, a nickel to be thrust into the grip of the springs 7 and 8, and presented to the conductor, requiring only one hand in the operation, and requiring no attention on the part of the passenger, as only a single coin is accessible to the conductor.

I claim,

1. A coin holder, comprising a flattened tube open at one end, a partition dividing 10 said tube into two coin holding chambers, a coin delivery member held on the open end of said tube and having a single coin passage therethrough in registration with one only of said coin chambers, said member 15 being removable, to register its passage with the other of said coin chambers.
2. A coin holder comprising a flattened tube open at one end and inclosing two coin chambers, a removable nozzle held on the

open end of said tube having one of its 20 sides offset to close one of said coin chambers, and having a passage for the delivery of coins therethrough, provided with yielding means for holding a coin with a portion of its surface beyond the end of said nozzle. 25

3. A coin holder comprising a flattened tube open at one end, and having a central longitudinal partition forming two coin chambers, a removable nozzle held on the open end of said tube and having a passage 30 for the delivery of coins therethrough, said passage being adapted to register with either one of said coin chambers.

Dated this sixth day of April, 1916.

FRANK M. MEAD
